UNITED STATES PATENT OFFICE

ROBERT M. MUTCHE, OF SOUTH HADLEY FALLS, MASSACHUSETTS

SAFETY GUARD APPARATUS FOR PLATERS

Application filed November 19, 1927. Serial No. 234,499.

This invention relates to improvements in safety guard apparatus for platers and the like.

The invention is adapted for use generally in connection with calenders having a pair of rolls between which material is passed for some step in a manufacturing operation; but in order to facilitate a clear understanding of the invention it will be described in connection with a paper finishing or embossing plater of well known form.

Such a plater usually comprises a pair of heavy rotatable pressure rolls which are relatively adjustable towards and away from one another and arranged to rotate in one direction and the other. A book or pack is passed back and forth between the rolls for the finishing or embossing operation by an operator, the book comprising alternate layers of paper and cloth or other material for impressing the paper with the impression or finish desired. Inasmuch as the operator manipulates the book back and forth through the bite between the rolls by hand, there is grave danger of the operator having one or both of his hands caught or carried between the rolls. Accordingly, it is one object of this invention to provide a guard which is arranged to move up and down in front of the bite of the rolls so as to close up or stop off the entrance to the bite of the rolls and thereby prevent the entrance of the operator's hands therebetween. According to another feature of the invention, I provide means for operating the guard which is actuated by or under the control of the book whereby the guard is moved between its guarding position or away therefrom accordingly as the pack is moved into or out of the bite of the rolls.

Other objects and advantages will be observed from the following description of the invention which is illustrated in the form at present preferred by means of the accompanying drawings, in which:

Fig. 1 is a front elevational view of a finishing plater of well known form having the novel features of my invention attached thereto;

Fig. 2 is a sectional view taken on the line

2—2 of Fig. 1 with parts of the plater omitted for clearness; and

Fig. 3 is a sectional elevational view taken on the line 3—3 of Fig. 2.

Referring to the drawings in detail: the plater of well known form comprises side frames such as 1 and 1 in which are journalled upper and lower pressure rolls 2 and 3. The rolls are geared together in the ordinary way by gears 4 (as shown) and are arranged to be moved towards and away from one another so as to exert pressure on books of various thicknesses. Other means (not shown) are provided in the ordinary plater to operate the rolls first in one direction and then the other so that a book may be rolled back and forth therebetween for the rolling and pressing action. An apron 5 is provided which extends forwardly of the rolls and is properly secured to the frames 1 and 1. A plurality of book rollers 6 are journalled in the apron 5 and are adapted to support a book so that it may be moved back and forth into and out of the bite of the rolls 2 and 3.

A roller 10, forming a part of my invention, is also journalled in the apron and has a shaft 11 which extends through a casing 12 and at its outer end is journalled therein as shown in Fig. 3. This roller is preferably larger in diameter than the rollers 6 so that a book will rest thereon or frictionally engage and rotate the same in one direction or the other as the book is moved back and forth.

A guard G arranged to lie in front of the bite of the rolls 2 and 3 is slidable up and down in suitable guideways 12 fixed to the calender frames 1 and 1, and is preferably provided with a roller 13 journalled at the lower side thereof so that the guard may rest on the upper side of a book as it is moved back and forth.

Guide pulleys 14, 15, and 16 are provided to support and guide cables 18 and 19 secured to the guide, while the latter has its end secured to a winding or take-up drum 20 fixed to the shaft 11. The parts thus far described are preferably constructed and arranged so that as the roll 10 is rotated in the direction of the arrows α by the book as it is

fed forwardly between the rolls 2 and 3, the drum 20 will wind up the cable 19 to elevate the guard to allow the book to pass thereunder; while as the book is moved away from the rolls the roll 10 will be rotated in the opposite direction to unwind the cable so as to allow the guard to move to its guarding position in front of the bite between the rolls.

10 If books were alike as to thickness and length, the apparatus described could be adjusted so that the guard would be elevated to a proper height above a book just as the forward end of the book reaches it in its forward movement and allowed to drop again just as said end passes under it in its rearward movement. But books are commonly employed which are of various thicknesses and lengths and accordingly the following 15 mechanism is provided to operate the guard when either the thickest book or the longest book is being used.

Accordingly, brake drum 24 is provided which is fixed to the shaft 11 and a brake 25 lever 26 pivoted to the casing carries on one end a spring member 17 which is adapted to engage said brake drum 24 and to function as a brake shoe accordingly as the lever is engaged by and rocked in a counterclockwise direction by a coil spring 25, as will later appear.

The coil spring 25 preferably surrounds the shaft 11 and is in the form of a flat clock spring of well known form and has its inner 35 end fixed to said shaft 11 while its outer end is fixed to the casing 12 in the well known manner. It is wound or arranged so that as the roller 10 is rotated in a direction opposite to that indicated by the arrow α , it 40 will be rolled or wound up. When the roller is rotated in the direction of the arrow α , the spring will be unwound and its diameter increased so that its periphery will engage and actuate the lever 26 so that the brake 17 45 is applied to the drum to hold the roller from rotation.

In operation, the guard is normally in its lowered or guarding position in front of the bite of the rolls 2 and 3, and the cable 19 is 50 taut. As the pressure rolls 2 and 3 of the calender are rotated, a book comprising the layers of paper and imprinting material is laid upon the rollers 6 and 10 and fed forwardly by the operator. The forward movement of the book rotates the roller 10 so as to wind up the cable and elevate the guard and at the same time unwind the spring 25. In the case of an extremely long book, the roll 10 would be rotated to such an extent that the 55 cable would move the guard up away from the upper side of the book to form a space between the lower edge of the guard and book. This is avoided by limiting the rotation of the roller and is accomplished by 60 means of the brake lever 26 which forces the

brake spring or shoe 17 onto the drum as the lever is actuated by the spring 25.

As the book is returned onto the apron or away from the rolls, the roll 10 is rotated so as to wind up the spring 25 and unwind the cable. The unwinding of the cable provides slack and allows the guard to bear on the book so that as the end of the book passes beneath the guard it may fall downwardly to its guarding position between the end of the book and bite of the rolls. When the book is lifted from the roller 10, the spring will 70 rotate the roller and drum to take up the slack (if any) in the cable so that as another book is placed on the apron and roller 10, the guard will be elevated at the proper time by rotation of the roller 10.

From the foregoing it will be observed that I have provided a guard which is movable towards and away from the bite of the rolls and which is operable by means under the control of the book being calendered.

I am aware that many changes may be made in the form of the invention without departing from the scope thereof, and I therefore prefer to be limited by the appended claims rather than by the foregoing description of the invention.

What I claim is:

1. Safety guard apparatus for a plater having coacting pressure rolls comprising in combination, a guard movable towards and away from the bite of said rolls, a roller for supporting material to be plated and connections between said roller and guard whereby the latter is operated by the former between guarding and non-guarding positions accordingly as the material is moved towards and away from the bite of said rolls.

2. Safety guard apparatus for a plater having coacting pressure rolls comprising in combination, a guard slidable between a non-guarding position and a guarding position in front of the bite of said rolls, a roller for supporting material to be moved back and forth between said rolls, and means operable thereby for moving said guard between the positions specified accordingly as said roller is rotated in one direction or the other.

3. Safety guard apparatus for a plater having coacting pressure rolls comprising in combination, a guard slidable between a non-guarding and a guarding position in front of the bite of said rolls, a roll for supporting material to be moved back and forth between said pressure rolls, a drum rotated by said roll, and a cable connected to said guard and to said drum whereby the guard is moved from its guarding position accordingly as material is moved towards said pressure rolls.

4. Safety guard apparatus for a plater having coacting pressure rolls comprising in combination, a guard slidable between a non-guarding position and a guarding position in front of the bite of said rolls, a roller for

supporting material to be moved back and forth between said rollers, a drum rotatable by said roller, a cable connected to said guard and to said drum whereby the guard is operated and means for limiting the rotation of said roller in one direction.

In testimony whereof I have affixed my signature.

ROBERT M. MUTCHE.
